UNITED STATES PATENT OFFICE.

WILLIAM H. GIBBS AND GEORGE W. SNOOK, OF HOPEWELL, NEW JERSEY.

COMBINED RAILROAD TIE AND CHAIR.

SPECIFICATION forming part of Letters Patent No. 274,309, dated March 20, 1883.

Application filed July 7, 1882. (No model.)

To all whom it may concern:

Be it known that we, WILLIAM H. GIBBS and GEORGE W. SNOOK, of Hopewell, in the county of Mercer and State of New Jersey, have invented a new and useful Improvement 5 in Combined Railroad Ties and Chairs, of which the following is a full, clear, and exact description.

Reference is to be had to the accompanying 10 drawings, forming a part of this specification, in which similar letters of reference indicate corresponding parts in all the figures.

Figure 1 is a side elevation, partly in section, of a part of our improvement, and showing a 15 rail in place. Fig. 2 is a plan view of one end of a tie. Fig. 3 is a sectional elevation of the improvement, taken through the line $\alpha\alpha$, Fig. 1. Fig. 4 is a perspective view of one of the spikes.

20 The object of this invention is to promote convenience in surfacing railroad-tracks, facilitate the repairing and leveling of the tracks, and increase the durability of the ties and chairs.

25 The invention consists in a combined railroad tie and chair constructed with a tie provided with a top flange, pairs of inclined cross-flanges having angular grooves, and a lug to receive the chair. The chair is made with a central offset to receive a block to support the rail, and downwardly-inclined side parts to 30 interlock with the grooved cross-flanges of the tie, and has slots formed in its side parts to receive the spikes and locking-screws, and lugs to prevent the locking-nuts from turning, all 35 constructed and operating as will be herein-after fully described.

A represents a tie which is made of wrought or cast iron. Upon the upper side of the tie 40 A is formed a longitudinal flange or web, C, having cross-flanges D at its end parts. The two cross-flanges D, at each end of the tie, incline toward each other, and have angular grooves E in the inner sides of their upper edges to receive the beveled edges of the chair F. The chair F is made with a downward offset in its middle part to rest upon a lug, G, formed upon the tie A, midway between the two cross-flanges D, and to form a seat for the wooden block H, upon which the rail I rests. The side parts of the chair F project horizon-

tally, incline downward, and their edges project horizontally, and are beveled to fit into the grooves E and prevent the said chair from rising from its support.

55 J are the spikes, which have shoulders or L-shaped heads K upon their upper ends to rest upon the flanges of the rail I. The spikes J are inserted in slots in the horizontal parts of the chair F, and have outwardly-projecting shoulders L upon their lower ends, in which are formed indentations or recesses to receive the conical ends of the screws M and prevent the said ends from slipping off the said shoulders L. The screws M pass down through the 60 slots in the horizontal parts of the chair F, and through nuts N, placed beneath the said horizontal parts of the chair. The nuts N fit into the spaces between the spikes J and lugs or shoulders O, formed upon the upper part of 65 the inner surface of the inclined side parts of the chair, so that the said nuts will be held from turning, will hold the spikes J from any outward movement, and will thus prevent the heads K from slipping off the flanges of the 70 rail I. With this construction the chairs can also be used upon ties made of wood, stone, glass, or any other suitable material. With this construction the rails can be leveled without disturbing the ties by varying the thickness of the wooden blocks H.

Having thus described our invention, we claim as new and desire to secure by Letters Patent—

1. A combined railroad tie and chair constructed substantially as herein shown and described, and consisting of the tie A, provided with the top flange, C, and the inclined cross-flanges D, having angular grooves E, the chair F, provided with central offset, the spikes J, 85 and the screws M and nuts N, as set forth.

2. In a combined railroad tie and chair, the tie constructed substantially as herein shown and described, and consisting of the body A, provided with the top flange, C, the pairs of inclined cross-flanges D, having angular grooves E, and the lug G to adapt the tie to receive and support the chair, as set forth.

3. In a combined railroad tie and chair, the chair F, made, substantially as herein shown 90 and described, with central offset to receive the rail-supporting block H, slots to receive

the spikes J and locking-screws M, downwardly-inclined sides having beveled edges to enter grooves in the tie-flanges, and shoulders O to hold the nuts, as set forth.

5. 4. In a combined railroad tie and chair, the combination, with the chair F, of the wooden block H, the spikes J, having shoulders K L, the screws M, and the nuts N, substantially as herein shown and described, whereby the

rail will be supported at any height and can be readily connected with and released from the chair, as set forth.

WILLIAM H. GIBBS.
GEORGE W. SNOOK.
